OIL BURNER EVAPORATOR

Gordon C. Kemp, Guelph, Ontario, Canada

Application November 10, 1951, Serial No. 255,780

11 Claims. (Cl. 158—92)

1

This invention generally relates to an oil burner of the vaporizing type, and is a continuation-in-part of application Serial No. 94,869, filed on the 23rd day of May 1949 and now abandoned.

In oil burners of the vaporizing type liquid fuel oil is introduced into a heated chamber where it is vaporized and mixed with a primary supply of air. As the mixture rich in oil forms, it expands, begins to burn, and moves through the chamber. Subsequently, what is commonly called a secondary supply of air is added to the mixture in an amount sufficient to support complete combustion of the oil.

Most burners of the vaporizing type have been vertical. That is, the fuel oil is introduced onto a horizontal base and the vapors rise therefrom vertically. One difficulty encountered with the vertical type vaporizing burner has been the excessive amounts of carbon that result from the quick rise of the burning mixture of oil and air as they rise before they have an opportunity to heat the sides of the vaporizing chamber. There have been attempts to overcome carbon from this cause by constructing a vaporizing burner in which the vapors move in a substantially horizontal direction. They have, however, had only limited success in reducing the carbon, and with most of them it is necessary to use a relatively highly refined oil to obtain a reasonably clean fire.

The burner of this invention is a horizontal type burner, that is, the vapors as they are formed move in a substantially horizontal direction, but with the present burner the temperature of the base of the vaporizing chamber is substantially higher with the result that the formation of carbon is substantially eliminated even when oils of a lower grade than those customarily used in burners of this general class are burned.

Generally speaking, a burner according to the present invention has an oil vaporizing and mixing chamber with a mouth at its front end through which vapors and gases can move in a substantially horizontal direction. The base of the vaporizing and mixing chamber, over which the gases and vapors proceed as they travel towards the mouth, slopes rearwardly and downwardly from the mouth. According to the invention a plurality of primary air jets and a plurality of secondary air jets are arranged in the chamber to overlie the base, the secondary air jets being in advance of the primary air jets and both the primary and secondary air jets being uniformly spaced apart over a combined area that overlies substantially all of the base within the vapor-

2

izing and mixing chamber. The jets are arranged to direct an air stream therefrom downwardly against the base. Means are, of course, provided for forcing air through the primary and secondary jets against the base and for admitting fuel oil to the rear of the base. The burner that I have found most satisfactory has, in addition to the inclined portion of the base, a horizontal portion that merges with the inclined portion, and an extension that projects beyond said mouth in the same plane as the sloping portion thereof.

The invention will be clearly understood after reference to the following detailed specification read in conjunction with the drawings.

15 In the drawings,

Figure 1 is a sectional elevational view of a burner according to the invention.

Figure 2 is a plan view taken along the line 2—2 of Figure 1, and

Figure 3 is a view showing a burner installed in a hot air furnace.

Referring to the drawings, the letter A generally indicates an oil burner, or more accurately perhaps an oil vaporizer, according to the present invention. It comprises a casing formed with an air admitting chamber 10 and an oil vaporizing and mixing chamber 11, the latter chamber having a mouth 12 at its front end through which vapors and gases can move in a substantially horizontal direction.

The base 13 of the vaporizing and mixing chamber 11 slopes rearwardly and downwardly from the open mouth 12 as at 14 and merges with a horizontal portion 15 adjacent the back thereof. Preferably the base 13 of the vaporizing and mixing chamber 11 is formed with an extension 16 that projects beyond the mouth 12 in the same plane as the sloping portion 14.

Numerical 17 refers to an oil inlet tube for admitting oil to the rear horizontal portion 15 of the base 13. Preferably the rear horizontal portion 15 of the base 13 has two upstanding ridges 19, one on each side of the oil inlet tube 17. These ridges serve to guide the incoming oil to a central position on horizontal base 15 and gives controlled distribution of vaporized gases in chamber 11.

According to the invention, primary and secondary air, to achieve vaporization and support combustion of oil admitted to the chamber 11, is introduced thereto through a series of primary and secondary air jets that are uniformly spaced apart over a combined area that overlies substantially all of the base 13 of the vaporizing and mixing chamber 11. The jets are pointed to di-

rect air therefrom downwardly on the base. In the embodiment of the invention shown, the air admitting chamber 10 overlies the combustion chamber 11 and is separated therefrom by means of the plate 18. The plate 18 is arranged to overlie the base 13 so that it is substantially parallel to the sloping portion 14 thereof and the aforementioned jets comprise holes drilled in the plate 18. The primary air jets are behind the secondary air jets and comprise a series of relatively small holes 19a drilled in the rear portion of plate 18 at uniformly spaced apart intervals. The secondary air jets comprise larger holes 20 formed in the plate 18 in advance of the holes 19a. The primary air is admitted for the purpose of vaporizing and mixing with the oil vapors as they rise from the hot base 13 in operation. The holes 20 are large enough to ensure that the secondary air is added in sufficient amounts to achieve complete combustion of the oil admitted after preliminary or primary mixing of oil and air. The principles governing the admission of primary and secondary air in oil burners are well known and need not be gone into in this specification in detail. To do so would only unnecessarily burden it.

It will be apparent that with the plate 18 mounted in substantially parallel relation to the sloping portion 14 of the base 13 that air passing through the primary and secondary jets will move downwardly onto the base at substantially right angles if driven through the jet openings with sufficient force.

In the embodiment of the invention shown a motor 21 drives a fan (not shown) to force air in through the opening 22 of the air admitting chamber 10 and force it around the baffles 23 and 24 down through the jet openings 19a and 20 with sufficient force to cause it to strike the base 13 during operation. Baffles 23 and 24 are introduced to achieve an even distribution of the air, taken in through opening 22 over all of the jet holes in the plate 18. Baffle 24 is also provided to stop oil flowing back into air chamber 10 through holes in plate 18 if at any time chamber 11 became flooded with oil.

The base 13 of the combustion chamber 11 is preferably cast and of substantial thickness as indicated, to withstand the high operating temperatures that are attained in high fire operation by reason of the jet-like manner in which primary and secondary air is introduced over the entire base area. When the burner operates on high fire the sloping portion 14 of the base 13 reaches a temperature of about 1700° F., a temperature too high for the formation of carbon.

The burner could be fabricated in a variety of ways. It is convenient, however, to cast the base, baffle 24, front wall 25, and side walls 26 and plate 18 in one piece, form the portion of the air admitting chamber 10 behind the baffle 24 in one piece and secure it to the forward section of the casing by bolts, and form the top plate 27 separately and weld it into position. Baffle 23 is also formed separately and welded into position. The air intake 22 and oil inlet 17 are secured by any suitable means.

It will, of course, be understood by those skilled in the art that the burner so far described is for use in a combustion chamber 28 of a furnace such as the one 29 illustrated in Figure 3. In use, the motor 21 drives the fan, only the housing 21a of which is shown, to force air into the opening 22 in sufficient amounts for the primary and secondary supply of air. The admission of oil

to the base of the vaporizing and combustion chamber 11 can be either manually or thermostatically controlled.

It will be appreciated that the amount of heat generated depends entirely on the amount of oil admitted to the vaporizing and combustion chamber 11. The burner is started as all other vaporizing type burners are started, that is, a small quantity of oil is admitted to the combustion chamber and ignited by means of a lighted wick or the like. At the same time, of course, the motor 21 drives the fan to supply air to the vaporizing and combustion chamber. If the burner is to be operated thermostatically, it will be necessary to maintain burning oil in the combustion chamber 11 at all times. The practice is to maintain this burning at a minimum when the thermostat does not demand heat and to increase the burning when the thermostat demands heat. One can successfully maintain a pilot flame with 2 cc. of oil per minute. Such a flow to the base of the vaporizing chamber can be controlled by well known means. On low fire the oil usually completely burns in the rear portion of the vaporizing chamber. On high fire, however, the oil upon admission is vaporized by the residual heat of the base portion and mixed with primary air forced through the jets 19a. These vapors are quite rich in oil and as they form they roll up the inclined portion 14 of the base and receive the secondary air through the holes 20. Partial combustion has taken place by the time the vapors reach the portion of the base that underlies secondary holes 20 and the base 13 becomes very hot as indicated above. The base is so hot that carbon cannot form. From the open mouth 12 of the vaporizing chamber the burning oil vapors, mixed with sufficient oxygen to support complete combustion, pass into the fire-pot 28 of the furnace 29, and completely burn.

As previously indicated, air is forced through the jets 19a and 20 with sufficient force to impinge upon the base 13. It is in this manner that a high base temperature within the burner is achieved to obtain an efficient substantially carbon-free vaporization of the oil.

When the burner operates on pilot flame or low fire the base temperature is in the neighbourhood of 900° F., but on the low rate of burning carbon does not readily form because there is always an excess of oxygen.

The burner can also be applied to domestic cooking ranges or stoves, in which case the rate of oil feed is manually controlled and usually is somewhat less than the high fire rate of feed when the burner is used in a furnace. In range and stove applications the vaporizing base 13 reaches a temperature of about 1200° F.

The dimensions of the burner are, of course, subject to variation without departing from my invention of providing a horizontal burner and evenly supplying primary and secondary air under pressure over substantially all of the base area thereof to secure a base operating temperature so high that carbon will not form.

What I claim as my invention is:

1. In a device for burning oil, an oil vaporizing and mixing chamber having imperforate side walls and a mouth at its front end through which vapors and gases can move, said vaporizing and mixing chamber having a base over which gases and vapors proceed as they travel towards said mouth that slopes rearwardly and downwardly from said mouth, means for causing primary and secondary air to strike against

said base including means for forming a plurality of primary air jets in said chamber overlying said base, and means for forming a plurality of secondary air jets in said chamber overlying said base, said means for forming said secondary air jets being closer to the mouth of said vaporizing and mixing chamber than said means for forming said primary air jets, said means for forming said primary and said secondary air jets being spaced apart over a combined area that overlies substantially all of said base within said vaporizing and mixing chamber and pointed to direct jets therefrom downwardly onto said base substantially at right angles thereto, means for admitting fuel oil to the rear of said base, means for forcing air through said means for forming said primary and secondary air jets and against said base, and said means forming said primary and secondary air jets constituting the sole supply means for air from said air forcing means.

2. A device for burning oil as claimed in claim 1, in which said base of said vaporizing and mixing chamber is formed with an extension that projects beyond said mouth in the same plane as the sloping portion thereof.

3. In a device for burning oil, an oil vaporizing and mixing chamber having imperforate side walls and a mouth at its front end through which vapors and gases can move, said vaporizing and mixing chamber having a base over which gases and vapors proceed as they travel towards said mouth that slopes rearwardly and downwardly from said mouth, said base of said vaporizing and mixing chamber having a horizontal as well as a sloping section, said horizontal section being at the rear thereof and merging with said sloping section, means for causing primary and secondary air to strike against said base including means for forming a plurality of primary air jets in said chamber overlying said base, and means for forming a plurality of secondary air jets in said chamber overlying said base, said means for forming said secondary air jets being closer to the mouth of said vaporizing and mixing chamber than said means for forming said primary air jets, said means for forming said primary and said secondary air jets being uniformly spaced apart over an area that overlies substantially all of said base within said vaporizing and mixing chamber and pointed to direct jets therefrom towards said base substantially at right angles thereto, means for admitting fuel oil to the rear of said base, means for forcing air through said means for forming said primary and secondary air jets and against said base and said means forming said primary and secondary air jets constituting the sole supply means for air from said air forcing means.

4. A device for burning oil as claimed in claim 3 in which said base of said vaporizing and mixing chamber is formed with an extension that extends beyond said mouth in the same plane as the sloping portion thereof.

5. A device for burning oil comprising a casing, said casing being formed with an air admitting chamber and an oil vaporizing and mixing chamber, said vaporizing and mixing chamber having imperforate side walls and a mouth at its front end through which vapors and gases can move, said vaporizing and mixing chamber having a base over which gases and vapors proceed as they travel toward said mouth that slopes rearwardly and downwardly from said mouth, said air admitting chamber overlying said vapor-

izing and mixing chamber and being separated therefrom by a partition, said partition being formed with a plurality of holes that serve as primary air jets, said partition further being formed with a plurality of holes that serve as secondary air jets, said primary and said secondary air jets being spaced over a combined area that overlies substantially all of the said base within said vaporizing and mixing chamber, said secondary jets being closer to the mouth of said vaporizing and mixing chamber than said primary jets, said partition in which said primary and said secondary jets are formed being substantially parallel to said base as it slopes away from said mouth to direct an air stream therefrom toward said base, said air admitting chamber having an air inlet, means for admitting fuel oil to the rear of said base, means for drawing air into said air admitting chamber and forcing it through said holes in said partition that separates said air admitting chamber from said oil vaporizing and mixing chamber to strike against said base, and said holes formed in said partition constituting the sole supply means for air to said vaporizing and mixing chamber from said air forcing means.

6. A device for burning oil as claimed in claim 5 in which said base of said vaporizing and mixing chamber is formed with an extension that extends beyond said mouth in the same plane as the sloping portion thereof.

7. A device for burning oil comprising, a casing, said casing being formed with an air admitting chamber and with an oil vaporizing and mixing chamber, said vaporizing and mixing chamber having imperforate side walls and a mouth at its front end through which vapors and gases can move, said vaporizing and mixing chamber having a base over which gases and vapors proceed as they travel toward said mouth that slopes rearwardly and downwardly from said mouth, said base of said vaporizing and mixing chamber having a horizontal as well as a sloping section, said horizontal section being at the rear thereof and merging with said sloping section, said air admitting chamber overlying said vaporizing and mixing chamber and being separated therefrom by a partition, said partition being formed with a plurality of holes that serve as primary air jets, said partition further being formed with a plurality of holes that serve as secondary air jets, said primary and said secondary air jets being spaced over a combined area that overlies substantially all of said base within said vaporizing and mixing chamber, said secondary jets being closer to the mouth of said vaporizing and mixing chamber than said primary jets, said partition in which said jets are formed being substantially parallel to said base where it slopes away from said mouth to direct the air stream from the jets formed therein toward said base, said air admitting chamber having an air inlet, means for admitting fuel oil to the rear of said base, means for drawing air into said air admitting chamber and forcing it through said holes in said partition that separates said air admitting chamber from said oil vaporizing and mixing chamber and against said base, and said holes formed in said partition constituting the sole supply means for air to said vaporizing and mixing chamber from said air forcing means.

8. A device for burning oil as claimed in claim 7, in which said base is formed with an exten-

sion that extends beyond said mouth in the same plane as the sloping portion thereof.

9. A device for burning oil as claimed in claim 7, in which said base is formed with an extension that extends beyond said mouth in the same plane as the sloping portion thereof, and baffle means in said air admitting chamber to reduce the velocity of the air in said air admitting chamber above said partition.

10. In a device for burning oil, an oil vaporizing and mixing chamber having imperforate side walls and a mouth at its front end through which vapors and gases can move, said vaporizing and mixing chamber having a base over which gases and vapors proceed as they travel towards said mouth that slopes rearwardly and downwardly from said mouth, means for directing primary and secondary air to strike against said base including means for forming a plurality of primary air jets in said chamber overlying said base, means for forming a plurality of secondary air jets in said chamber overlying said base, said secondary air jets being closer to the mouth of said vaporizing and mixing chamber than said primary air jets, said means forming said primary and said secondary air jets being spaced apart over a combined area that overlies substantially all of said base within said vaporizing and mixing chamber and pointed to direct air therefrom downwardly onto said base substantially at right angles thereto, means for admitting fuel oil to the rear of said base, and said means forming said primary and said secondary air jets being the sole means for admitting air to said vaporizing and mixing chamber.

11. A device for burning oil comprising, a casing, said casing being formed with an air admitting chamber and with an oil vaporizing and mixing chamber, said vaporizing and mixing

chamber having imperforate side walls and a mouth at its front end through which vapors and gases can move, said vaporizing and mixing chamber having a base over which gases and vapors proceed as they travel toward said mouth that slopes rearwardly and downwardly from said mouth, said base of said vaporizing and mixing chamber having a horizontal as well as a sloping section, said horizontal section being at the rear thereof and merging with said sloping section, said air admitting chamber overlying said vaporizing and mixing chamber and being separated therefrom by a partition, said partition being formed with a plurality of holes that serve as primary air jets, said partition further being formed with a plurality of holes that serve as secondary air jets, said primary and said secondary air jets being spaced over a combined area that overlies substantially all of said base within said vaporizing and mixing chamber, said secondary jets being closer to the mouth of said vaporizing and mixing chamber than said primary jets, said partition in which said jets are formed being substantially parallel to said base where it slopes away from said mouth to direct the air stream from the jets formed therein to strike said base, said air admitting chamber having an air inlet, means for admitting fuel oil to the rear of said base, and said holes formed in said partition being the sole means for admitting air to said vaporizing and mixing chamber.
